(57) **CLAIM**

We claim the ornamental design for a wireless notebook adapter, substantially as shown and described.

DESCRIPTION

FIG. 1 is a top view of the wireless notebook adapter according to one embodiment;

FIG. 2 is a perspective view of the wireless notebook adapter of FIG. 1;

FIG. 3 is a side view of the wireless notebook adapter of FIG. 1, the opposite side view being a mirror image thereof; and,

FIG. 4 is a front view of the wireless notebook adapter of FIG. 1.
